CLAIM

The ornamental design for a sun screen cover for mobile phone, as shown and described.

DESCRIPTION

FIG. 1 is a top perspective view of a sun screen cover for mobile phone;

FIG. 2 is a front elevation view of the sun screen cover for mobile phone;

FIG. 3 is a back elevation view of the sun screen cover for mobile phone;

FIG. 4 is a top plan view of the sun screen cover for mobile phone;

FIG. 5 is a bottom plan view of the sun screen cover for mobile phone;

FIG. 6 is a left side elevational view of the sun screen cover for mobile phone;

FIG. 7 is a right side elevational view of the sun screen cover for mobile phone; and,

FIG. 8 is a top perspective view of the sun screen cover for mobile phone attached to a mobile phone.

In FIG. 8, the broken lines showing a mobile phone illustrate the environment in which the ornamental design for the sun screen cover for mobile phone is used and forms no part of the claimed design.

1 Claim, 5 Drawing Sheets
